UNITED STATES PATENT OFFICE.

EUGENE McLEAN LONG, OF NEW YORK, N. Y.

AUTOMATIC SPRINKLER-HEAD.

1,026,687.

Specification of Letters Patent.

Patented May 21, 1912.

Application filed August 2, 1911. Serial No. 642,037.

To all whom it may concern:

Be it known that I, EUGENE McLEAN LONG, a citizen of the United States, residing at New York city, in the State of 5 New York, have invented certain new and useful Improvements in Automatic Sprinkler-Heads; and I do hereby declare the following to be a full, clear, and exact description of the invention, such as will enable others skilled in the art to which it appertains to make and use the same, reference being had to the accompanying drawings, and to the letters and figures of reference marked thereon, which form a part 10 of this specification.

This invention relates to certain new and useful improvements in that class of sprinkler heads which are applied in connection with pipe systems in buildings and in which 20 the pipes with which the sprinkled heads are connected are normally closed, the closure being normally held in position by thermostatically actuated mechanism which, in the present instance, depends for its action 25 upon the fusing of metal.

The invention has for its object the provision of a simple, inexpensive and practical device of this character, the action of which may be at all times depended upon 30 by the temperature of the apartment in which the sprinkler head is located rising to such a point as to insure the melting of the fusible metal employed to hold the trigger or locking bar in position.

To these ends and to such others as the invention may pertain, the same consists in the peculiar construction and in the novel combination, arrangement and adaptation 35 of parts, all as will be more fully herein-after described, shown in the accompanying drawings and then specifically defined in the appended claims.

The invention is illustrated in the accompanying drawings, which, with the letters of reference marked thereon, form a part of this specification and in which:—

Figure 1 is a side elevation, partly in section of a sprinkler head embodying my invention. Fig. 2 is an enlarged detail in perspective of one of the detachable valve holding parts. Fig. 3 is a like view of the opposing member. Fig. 4 is a perspective view of the trigger plate, and Fig. 5 is a top plan view of the deflector plate.

Reference now being had to the details of the drawings by letter, A represents the

branch pipe connected with the water pipe system of the building. B, B are side arms of a bracket member which at its lower end is connected with the pipe A.

F is a spherical body, preferably of glass or other suitable material, and forms the valve controlling the outlet from the pipe A, said valve being provided with a seat for the valve and which seat may be of rubber, metal or other substance adapted for the purpose, the seat being indicated by letter E and is seated upon the shoulder D formed for its reception around the outlet opening.

The spherical valve F is held to its seat by means of the plates I and K, the lower ends of which plates rest upon opposite sides of the sphere, the upper ends of said plates being inwardly inclined. The plate 75 I is provided with laterally extended arms I' which, at their free ends, are provided with shoulders I² for the reception of a trigger or releasing plate L, the plate L being at its lower edge provided with an outwardly flaring portion L' adapted, when in use, to engage the shoulder I² upon the arms I'.

The trigger end of the plate is held normally against the upper portion of the inclined plate K and is secured at its upper end, as shown at M, by means of a metal which is adapted to fuse at a low temperature. The inclined plates I and K unite at their upper ends in a depression G' in the 90 center of the lower face of the deflecting plate G. The said deflecting plate G is preferably spherical in outline and is made of sheet metal of a resilient nature, the plate being in cross section substantially convexed 95 with its outer periphery curved downward, as shown clearly in Fig. 1 of the drawings.

From the foregoing description, the operation of the device will be readily understood. It being assumed that the pipe system with which the head is connected is normally filled with water under pressure and is normally prevented from escaping through the pipe A by means of the spherical valve F seated within the entrance and held in its locked position by means of the mechanism above described and as shown clearly in Fig. 1 of the drawings. In case of fire in the apartment which is provided with the device, the temperature within the 105 room having risen to a point required to fuse the metal lock M, the fusing of the metal 110

will result in the throwing out or detaching of the trigger plate L by the outward pressure exerted upon the lower ends of the said plates, the said plates I and K, having 5 been thus released, are thrown outwardly, permitting the water pressure to unseat the valve F and the water is thrown against the lower face of the deflecting plate G and holder H and is deflected and distributed.

10 Having thus described my invention, what I claim to be new and desire to secure by Letters Patent is:—

15 1. In a sprinkler head of the character described, the combination with the head, communicating with the pipe system, of a spherical valve, a deflector plate positioned in a line extending through the center of the valve and outlet, valve locking mechanism consisting of inclined plates or members, the lower ends of which are in contact 20

with the valve upon opposite sides thereof and are held in their locked position by means of a trigger controlled by fusible metal.

2. In a sprinkler head, the combination 25 with a suitable frame and valve stopper, of a locking or holding device for the stopper consisting of two inclined members held in their relationship by the ends in contact being confined, and the opposite ends being held in place by a wedge shaped or spherical surface and a trigger plate normally secured by means of fusible metal, substantially as set forth.

30 In testimony whereof I hereunto affix my signature in the presence of two witnesses.

EUGENE MCLEAN LONG.
